Primary Examiner — Elizabeth J Oswecki*Assistant Examiner* — Yelizaveta Y Masalimova(74) *Attorney, Agent, or Firm* — Merchant & Gould P.C.(57) **CLAIM**

The ornamental design for an outsole tread, as shown and described.

DESCRIPTION

FIG. 1 is front, top and left side perspective view of an outsole tread showing our new design;

FIG. 2 is a left side elevation view thereof;

FIG. 3 is a right side elevation view thereof;

FIG. 4 is a front view thereof;

FIG. 5 is a back view thereof;

FIG. 6 is a top plan view thereof;

FIG. 7 is a bottom plan view thereof; and,

FIG. 8 is a back, bottom and left side perspective view thereof.

The portions shown in broken lines form no part of the claimed design.
